4-TERT.-HYDROCARBON-1,2-DIPHENYL-3,5-DIOXO-PYRAZOLIDINES AND PROCESS

Albrecht Heymons, Berlin-Nikolassee, Hans Volk, Berlin-Tempelhof, and Helmut Gansau, Berlin-Siemensstadt, Germany, assignors to Firma Riedel-De Haen Aktiengesellschaft, Seelze, near Hannover, Germany, a firm of Germany

No Drawing. Application December 14, 1954
Serial No. 475,296

Claims priority, application Germany January 8, 1954

9 Claims. (Cl. 260—310)

The anti-pyretic and analgetic action of 1,2-diaryl-3,5-dioxo-pyrazolidines which are substituted by a primary or secondary alkyl group is known. Of these alkylated derivatives, 4-n-butyl-1,2-diphenyl-3,5-dioxo-pyrazolidine, more particularly, has been able to achieve great significance and to find a wide therapeutic employment.

It has now surprisingly been found that compounds with even more favorable therapeutic properties than the aforementioned 4-n-butyl derivative are obtained if, instead of a primary or secondary alkyl group, a tertiary alkyl group, and more particularly the tertiary butyl group, is introduced into the 4-position of the 1,2-diphenyl-3,5-dioxo-pyrazolidines. It has further been found that like results are also obtained if the group in the 4-position is a 1-alkylcyclohexyl group. The resultant 1,2-diphenyl-3,5-dioxo-pyrazolidine derivatives, and particularly that substituted by the tertiary butyl group, are distinguished by an essentially lower toxicity and by an enhanced antiphlogistic action while maintaining a comparable anti-pyretic and analgetic action, so that the therapeutic breadth of the new compounds of the present invention is significantly greater and more favorable than that of the known compounds of similar constitution. This effect is particularly realized by the combination of the sodium salts of the new pyrazolidine derivatives with 1-phenyl-2,3-dimethyl-4-dimethylaminopyrazolone, for which the new compounds of the present invention are excellent solvents.

The preferred 1,2-diphenyl-3,5-dioxo-4-tert. alkyl-pyrazolidines according to the present invention correspond to the formula

wherein each of R₁, R₂ and R₃ stands for a lower (saturated) alkyl group or R₁ and R₂ together with the central tertiary carbon atom form a cyclohexyl group and R₃ is a lower alkyl group, and wherein the sum of the carbon atoms in R₁+R₂+R₃ is at least 3 and at most 8. Thus, each of R₁, R₂ and R₃ may be a methyl group; or each of R₁, R₂ and R₃ may be an ethyl group; or R₁ and R₂ may each be a methyl group while R₃ is a propyl group; or one of R₁, R₂ and R₃ may be methyl while the other two are ethyl; or R₁ may be methyl, R₂ ethyl and R₃ propyl; or R₁ and R₂ may each be a propyl group while R₃ is a methyl or ethyl group; or R₁ and R₂ together with the central tertiary C atom form a cyclohexyl group and R₃ is methyl, ethyl or propyl; etc.

The phenyl groups in the 1- and 2-position may be substituted but such substituents do not appear to add to the pharmacological activity of the compounds.

2

The aforesaid 1,2-diphenyl-3,5-dioxo-4-tert. alkyl-pyrazolidines and 1,2-diphenyl-3,5-dioxo-4-(1'-alkylcyclohexyl)-pyrazolidines form well-defined salts with a wide variety of organic and inorganic bases, which bases and salts are therapeutically valuable because of their analgetic, antipyretic, antiphlogistic and sedative action. Thus, administered orally, e. g. in tablet form, they are useful in the treatment of arthritic conditions, gouty conditions, and the like.

10 Preferred among the aforesaid salts are the sodium and magnesium salts and those of ethylene-diamine, triethanolamine and trimethylamine. The salts are advantageously prepared from the corresponding pyrazolidines of the above-indicated formula I by treating with 15 an equimolecular quantity of an appropriate base, e. g. with aqueous caustic soda, ethylenediamine, aqueous caustic potash, aqueous sodium carbonate solution, sodium ethylate, etc.

The excellent therapeutic effect of the hitherto-unknown compounds of the present invention could not be foreseen since the literature describes only the primary and secondary 4-alkyl-1,2-diaryl-3,5-dioxo-pyrazolidines and of these only a very few have been found to be suitable for therapeutic purposes.

25 The new 1,2-diphenyl-3,5-dioxo-4-tert. alkyl- or -4-(1'-alkylcyclohexyl)-pyrazolidines are preferably prepared by the introduction of the tertiary alkyl group into the 4-position of a 1,2-diphenyl-3,5-dioxo-pyrazolidine. This is achieved for example by the condensation of a pyrazolidine with a ketone, followed by alkylation of the alkylidene or cyclohexylidene compound with alkylmagnesium halide and hydrolysis of the addition compound. This mode of procedure is particularly advantageous since the introduction of the tertiary alkyl group into the pyrazolidine can be carried out in practice very simply and with excellent yield.

30 The synthesis in this way of the aforesaid diphenyl-3,5-dioxo-pyrazolidines which contain a tertiary substituent in the 4-position is new in pyrazolidine chemistry. Such synthesis has to be regarded as unobvious and unexpected since there was a real reason to expect that the Grignard compounds would react primarily with the pyrazolidine nitrogen and the two oxo groups, and that the balance of the concurrent reactions would therefore be in favor of those reaction products which are not here desired. It is therefore surprising that the desired 1,2-diphenyl-3,5-dioxo-4-tert. alkyl-pyrazolidines are obtained by the action of alkylmagnesium halides on the diphenyl-dioxo-alkylidene- or -cyclohexylidene-pyrazolidines, and by the splitting (hydrolysis) of the thus-obtained intermediates.

35 The following examples set forth typical embodiments of the invention. In the said examples the parts and percentages, unless otherwise indicated, are by weight and the temperatures are in degrees centigrade. Parts by volume bear the same relationship to parts by weight as do milliliters to grams.

Example 1

40 To a conventionally prepared solution of 18.2 parts of methylmagnesium iodide in 100 parts by volume of ether, there are slowly added dropwise 29.2 parts of 1,2-diphenyl-3,5-dioxo-4-isopropylidene-pyrazolidine (prepared by boiling 1,2-diphenyl-3,5-dioxo-pyrazolidine in acetone) in solution in 200 parts by volume of ether. The mixture is then heated to boiling for 1/2 hour. Upon cooling, water is added and the mixture is acidified with 10% hydrochloric acid. The resultant directly precipitated 1,2-diphenyl-3,5-dioxo-4-tert. butyl-pyrazolidine, as well as that isolated from the ether solution, is recrystallized from alcohol. It is in the form of fine colorless

needles and has a melting point of 175°. By reacting with an equivalent quantity of an alcoholic sodium-ethylate solution, evaporating off the greater portion of the alcohol, and precipitating with ether, there is obtained the corresponding sodium salt which is readily soluble in water.

Example 2

A Grignard solution is prepared from 4.8 parts of magnesium and 21.8 parts of ethyl bromide in 100 parts by volume of diethyl ether. To this solution, there is added, dropwise and while stirring, a solution of 14.6 parts of 1,2-diphenyl-3,5-dioxo-4-isopropylidene-pyrazolidine in 300 parts by volume of diethyl ether. Upon completion of the ensuing reaction, the obtained organometallic intermediate compound settles out. The ether is removed by decantation, after which ice-water is added to the residue. After acidification with normal hydrochloric acid, the crude 1,2-diphenyl-3,5-dioxo-4-tert. amyl-pyrazolidine which is produced is isolated and dried. By recrystallization from toluene and then from methanol, this product is obtained as fine colorless needles which melt at 140.5° C. The yield amounts to about 60% of the theoretical yield.

In lieu of ethyl bromide, a corresponding quantity of ethyl iodide or of ethyl chloride may be used.

Example 3

A solution of 16.6 parts of 1,2-diphenyl-3,5-dioxo-4-cyclohexylidene-pyrazolidine in 350 parts by volume of diethyl ether-toluene mixture (2:1) is run, with stirring, into a Grignard solution, prepared from 4.8 parts of magnesium and 28.4 parts of methyl iodide in 100 parts by volume of diethyl ether. Upon completion of the reaction, the addition compound separates out. After decanting the solvent, ice-water is added to the residue which is then acidified with normal hydrochloric acid. The hydrolysate is isolated and recrystallized from methyl alcohol. The thus-obtained 1,2-diphenyl-3,5-dioxo-4-(1'-methylcyclohexyl)-pyrazolidine, which corresponds to the formula

is in the form of fine colorless needles which melt at 181°. The yield is about 60% of the theoretical.

Any other suitable hydrolyzing agent such, for example as dilute sulfuric acid, may be substituted for the hydrochloric acid, used by way of illustration, in the foregoing examples.

Having thus disclosed the invention, what is claimed is:

1. A compound selected from the group consisting of compounds corresponding to the formula

wherein each of R_1 , R_2 and R_3 stands for a lower alkyl group and wherein R_1 and R_2 may together with the adjacent C-atom represent a cyclohexyl group, the sum of the carbon atoms in $\text{R}_1+\text{R}_2+\text{R}_3$ being at least 3 and not more than 8, and the salts of such compounds with bases.

2. 1,2-diphenyl-3,5-dioxo-4-tert. butyl-pyrazolidine.

3. The sodium salt of 1,2-diphenyl-3,5-dioxo-4-tert. butyl-pyrazolidine.

4. 1,2-diphenyl-3,5-dioxo-4-tert. amyl-pyrazolidine.

5. 1,2-diphenyl-3,5-dioxo-4-(1'-methylcyclohexyl)-pyrazolidine.

6. A process for the preparation of a 1,2-diphenyl-3,5-dioxo-pyrazolidine containing a tertiary substituent in the 4-position, which comprises subjecting a member selected from the group consisting of a 1,2-diphenyl-3,5-dioxo-4-alkylidene-pyrazolidine and a 1,2-diphenyl-3,5-dioxo-4-cyclohexylidene-pyrazolidine to the action of an alkylmagnesium halide and then subjecting the resultant product to the action of hydrolyzing agent whereby the corresponding 4-tert. alkyl-substituted or 4-(1'-alkyl-cyclohexyl) - substituted 1,2-diphenyl-3,5-dioxo-pyrazolidine results.

7. A process for the preparation of 1,2-diphenyl-3,5-dioxo-4-tert. butyl-pyrazolidine, which comprises subjecting 1,2-diphenyl-3,5-dioxo-4-isopropylidene-pyrazolidine to the action of methylmagnesium iodide, and then subjecting the resultant product to the action of dilute hydrochloric acid whereby hydrolytic splitting takes place with formation of the 1,2-diphenyl-3,5-dioxo-4-tert. butyl-pyrazolidine.

8. A process for the preparation of 1,2-diphenyl-3,5-dioxo-4-tert. amyl-pyrazolidine, which comprises subjecting 1,2-diphenyl-3,5-dioxo-4-isopropylidene-pyrazolidine to the action of ethylmagnesium bromide, and then subjecting the resultant product to the action of dilute hydrochloric acid whereby hydrolytic splitting takes place with formation of the 1,2-diphenyl-3,5-dioxo-4-tert. amyl-pyrazolidine.

9. A process for the preparation of 1,2-diphenyl-3,5-dioxo-4-(1'-methylcyclohexyl)-pyrazolidine, which comprises subjecting 1,2-diphenyl-3,5-dioxo-4-cyclohexylidene-pyrazolidine to the action of methylmagnesium iodide, and then subjecting the resultant product to the action of dilute hydrochloric acid whereby hydrolytic splitting takes place with formation of the 1,2-diphenyl-3,5-dioxo-4-(1'-methylcyclohexyl)-pyrazolidine.
